UNITED STATES PATENT OFFICE.

RUDOLF WEIDE, OF BERLIN, GERMANY, ASSIGNOR TO HERMANN HURWITZ & CO., OF BERLIN, GERMANY.

PRINTING PRESS.

Application filed April 19, 1927, Serial No. 184,969, and in Germany April 19, 1926.

My invention relates to improvements in printing presses, and more particularly in printing presses comprising a rotary plate cylinder, and a rotary impression cylinder, and the object of the improvements is to provide a press of this type in which means are provided for positively guiding the sheet of paper from the feeding apparatus to the delivering apparatus. In machines as now constructed the sheet of paper tends to stick to the plate cylinder, and to be carried thereby away from its proper path. In my improved printing press this objection is obviated. It will be understood that various mechanical means may be provided for thus positively feeding the sheet of paper. For example, I may make use of feeding apparatus such as are used in machines of the textile art for feeding fabrics, the said apparatus comprising travelling tapes or bands and the like equipped with clamping means, needles, and the like. In the preferred construction described hereinafter the positive sheet feeding mechanism consists of a gripper adapted to grip the sheet of paper at its leading edge and to move the same at a velocity equal to the circumferential velocity of the plate cylinder to the delivering apparatus, and to release the same after it has been engaged by the said delivering apparatus. After having thus transmitted the sheet to the delivering apparatus, and after the sheet has been moved out of printing position, the gripper is removed into initial position for gripping another sheet.

For the purpose of explaining the invention an example embodying the same has been shown in the accompanying drawings in which the same reference characters have been used in all the views to indicate corresponding parts. In said drawings,

Fig. 1, is a diagrammatical elevation showing the printing apparatus and the means for positively guiding the sheet, the said means being in the position ready for engaging the leading edge of the sheet,

Fig. 2, is a similar elevation showing the parts in the position in which the stop has been retracted out of the path of the sheet and the jaws of the gripper have been closed on the said sheet,

Fig. 3, is a similar elevation showing the parts in the position in which the gripper has moved the leading edge of the sheet into posi-

tion for engaging the said delivering means, the jaws being still closed on the sheet,

Fig. 4, is a similar elevation showing the next step of the operation of the apparatus, the jaws of the gripper having released the sheet,

Fig. 5, is a similar elevation showing the next step of the operation, the mechanism operating the jaws being again locked to the mechanism for moving the gripper, and

Fig. 6, is a similar elevation showing the last step of the operation, the stop being in initial position, and the gripper being on its way to the said initial position.

In the example shown in the figures my improved printing press comprises a rotary plate cylinder D, a rotary impression cylinder A, the shafts W and m of the said cylinders being mounted in relatively fixed bearings, a feeding apparatus S for successively feeding sheets of paper from a pile thereof into position between the impression and plate cylinders, and a delivering apparatus comprising rollers u and v. In the operation of the machine the cylinder D is rotated in the direction of the arrow P, and the sheet of paper p is taken from a pile by means of the feeding apparatus S and fed thereby with its leading edge into engagement with a stop c', the said stop being disposed so that the leading part of the sheet is disposed between the impression and plate cylinders. The said stop c' is mounted on suitable gearing directly controlled from the plate cylinder and adapted to be retracted away from the plate cylinder when the plate of the plate cylinder D is in position for beginning printing. After the stop has thus been retracted the means for positively moving the sheet through the machine are thrown into operation.

In the construction shown by way of example in the figures, the said positive guiding means are in the form of a gripper comprising jaws a and b, and in the position of the parts shown in Fig. 1, in which a sheet p has just been passed between the cylinders and into engagement with the stops c', the jaws a and b are open for receiving the leading edge of the sheet. The jaws a and b are located between the stops c', so that both parts can simultaneously be in position for receiving the leading edge of the sheet.

For operating the gripper a, b two mechanisms are needed, one mechanism being pro-

vided for opening and closing the jaws *a* and *b*, and the second mechanism being provided for moving the gripper as a whole from the position shown in Fig. 1 into the position shown in Fig. 3 and for moving the sheet *p* into engagement with the delivering rollers *u* and *v*. The second mechanism is constructed so that the jaws are arrested after delivering the leading edge of the sheet, until the said sheet has been removed by the delivering rollers from the machine, whereupon it is returned into the position shown in Fig. 1 in which the jaws are ready for gripping another sheet. Both mechanisms controlling the movements of the jaws *a* and *b* depend on the printing operation, and they are timed so that the plate cylinder and the gripping apparatus move in unison while printing is performed. For this reason both mechanisms operating the gripper, viz the mechanism for opening and closing the jaws, and the mechanism for moving the gripper as a whole, are directly controlled from the plate cylinder *D* or the shaft *W* carrying the same. In the example shown in the figures the said mechanisms are controlled by means of cam disks *Z* provided one on each side of the plate cylinder and fixed either to the end faces thereof or to the shaft *W*, the said cam disks being thus uniformly rotated at the velocity of the plate cylinder. In addition, a controlling member *k* is fixed to the end face of the cylinder *D*. In the diagram illustrated in the figures the controlling member *k* is shown integral with one of the cam disks *Z*. But I wish it to be understood, that my invention is not limited to this feature, and that the construction has been shown merely by way of example. The cam disks *Z* cooperate with slides *Q* provided with rollers *Q'* engaging the cam disks *Z*, and the said slide is connected by a link *J* with an arm *j* secured to a rock shaft *c*. On the said rock shaft *c* a tubular member *s* is rockingly mounted, and to the said tubular member a disk *r* formed with a notch *t* is secured. Suitable means are provided for rocking the tubular member *s* in clockwise direction. To show what may be done a rope *2* carrying a weighted body *3* is trained on the tubular member in the manner shown in Fig. 1. I wish it to be understood that the said weighted body and rope have been shown merely by way of example, and that other means may be provided for rocking the tubular member *s* in clockwise direction, such for example as a spring-actuated mechanism. To the tubular member *s* an arm *x* is fixed, which is connected by a link *y* with an arm *z* secured to the upper jaw *b* of the gripper, the jaw *b* being rockable relatively to the jaw *a* by the mechanism just described. The jaw *a* is fixed to an arm *d* secured to the rock shaft *c*, so that its movement is controlled through the intermediary of the arm *d*, the rock shaft *c*, the arm *j*, the link *J*, the slide *Q* and the cam disk *Z* from the cylinder *D*.

der D. By the gripper and its operating mechanism thus described the leading edge of the sheet of paper is gripped at the proper time and positively moved thereby from the position shown in Fig. 1 into the position 70 shown in Figs. 3 and 4, whereupon the gripper is returned into initial position, the gearing y, z closing and opening the jaws a and b at the proper time.

The rocking movement of the tubular member s is controlled by two mechanisms. In the position shown in Fig. 1, the tubular member s is arrested in position by a roller n engaging in the notch t . The said roller n is mounted on a bell crank lever n' rockingly mounted on an arm o' of the rock shaft c at o , the said bell crank lever carrying a roller q . When rocking the system q, o, n in anti-clockwise direction the tubular member s and the parts connected therewith are rocked in clockwise direction by means of the weighted body 3. 75 80 85

The mechanism for thus rocking the system q, o, n is constructed as follows:

On the axis m of the impression cylinder A a lever l is rockingly mounted. When rocking the said lever in anti-clockwise direction a cam member m' engages the roller q and forces the same downwardly, so that the roller n disengages the notch t , a spring l' being provided for retracting the cam member m' away from the roller q . After the roller q has been released a spring n'' rocks the system q, o, n with the roller n into engagement with the disk r and the notch t thereof. The upwardly directed arm of the lever l carries a roller i which is in position for engagement by the cam member K.

Before feeding the sheet by means of the gripper a, b from the position shown in Fig. 1 into the position shown in Fig. 3 the stops c' are retracted out of the path of the said sheet. As shown, the said stops are mounted on an arm h^2 rockingly mounted at h' and rigidly connected with a lever d' . The said lever is acted upon by a spring d^2 , and it is connected with an arm e' carrying a roller g' located in position or engagement with the plate cylinder D, and more particularly with a cam f' provided thereon.

The operation of the feeding apparatus is 115 as follows:

In the position of the parts shown in Fig. 1 the leading edge of the sheet of paper has just arrived in position for engagement with the stops c' and the open gripper a, b , the plate cylinder D and the plate D' provided thereon are about to arrive in printing position and into engagement with the impression cylinder A, and the tubular member s is locked in position by the roller n . 120 125

As the plate cylinder D continues rotation, the parts are brought into the position shown in Fig. 2, in which the cam f' engages the roller g' so as to retract the stops c' through the intermediary of the gearing e', d', h', h², 130

and the cam K has rocked the lever l into the position in which the cam member m' has depressed the roller q, so that the roller n releases the disk r and the tubular member s, 5 the said tubular member having been rocked by the weighted body 3 in clockwise direction. Thereby the arm x and link y have rocked the arm z thus moving the jaw b towards the jaw a and gripping the leading 10 edge of the paper.

So far the slide Q has not been moved, and the gripper as a whole has been stationary. Upon further rotation of the plate cylinder D into the position shown in Fig. 3, the stops 15 c' remain in the position illustrated in Fig. 2, by reason of the circular form of the cam f'. But the cam disk Z acts through the intermediary of the slide and the link J on the rock shaft c so as to rock the arm d carrying the 20 gripper in clockwise direction. Thus the gripper, the jaws of which are closed on the sheet of paper is moved to the right, thus pulling the sheet p with its leading edge into position for engagement by the delivery rollers 25 u, v. The arm d and the link y are connected with each other by a spring y'. Thus the jaws remain in closed position while the gripper moves from the position shown in Fig. 1 into that shown in Fig. 2.

30 The rocking movement of the tubular member s and the disk r is arrested slightly after the parts have passed the positions shown in Fig. 3, by reason of an adjustable stop b' engaging an arm a' carried by the tubular member, the length of way between the position of the parts shown in Fig. 3 and that shown in Fig. 4 in which the arm a' engages the stop b' being such that at the end of the rocking movement of the disk r the jaws a, b are 40 again opened by the rocking movement of the shaft c and the gripper d into the position shown in Fig. 4, so that the leading edge of the sheet p is released. The position of the stop c' has not been changed. The bell crank 45 lever n, o, q, which is connected through the intermediary of the arm o' with the shaft c, and which therefore is likewise controlled by the cam disk Z, has continued its rocking movement in clockwise direction, while the 50 parts move from the positions shown in Fig. 4 into the position shown in Fig. 5, and its roller n engages again in the notch t, the disk r being arrested by the stop b'. Thus the tubular member s and the disk r are locked relatively to the shaft c and to the gearing controlled by the cam disk Z.

While the parts move from the position shown in Fig. 5 into that shown in Fig. 6, the slide Q is moved upwardly by the cam Z. 55 Thus the shaft c is rocked in anti-clockwise direction thus moving the arm d of the gripper and the tubular member s locked relatively to the said shaft by the roller n and all the parts carried thereby into initial positions. Simultaneously the cam f' has re-

leased the roller g', so that the lever d' is rocked by the spring d' in anti-clockwise direction, thus returning the stops c' into initial position, in which a new sheet p' is again arrested. 70

By the further movement of the cam disk Z in the direction of the arrow P the shaft c is further rocked in anti-clockwise direction, so that the arm d of the gripper is returned into the position shown in Fig. 1, in which 75 the open jaws engage the leading edge of the sheet. Now, upon further rotation of the plate cylinder D, the operation of the apparatus is repeated. 80

It may be found desirable under some circumstances to omit the stops c' completely. It will be noted that the gripper d is shown in Fig. 1 in a position to receive and retain the paper sheet prior to the printing operation regardless of the presence or absence of 85 the stops, and the function of the mechanism will not be materially altered by the omission of the latter.

While in describing the invention reference has been made to a particular example embodying the same I wish it to be understood that my invention is not limited to the construction shown in the drawings, and that various changes may be made in the general arrangement of the apparatus and the construction of its parts without departing from the invention. 90

I claim:

1. In a printing press, the combination, with a rotary plate cylinder, and a rotary impression cylinder, of means for feeding a sheet to said cylinders, means for delivering the sheet after printing, a gripper comprising a pair of clamping jaws adapted to grip the sheet, mechanism controlled by said plate cylinder for opening and closing said jaws, and mechanism controlled by said plate cylinder for moving said gripper from said cylinders to said delivering means. 105

2. In a printing press, the combination, with a rotary plate cylinder, and a rotary impression cylinder, of means for feeding a sheet to said cylinders, means for delivering the sheet after printing, a stop member for arresting the sheet being fed in position between said cylinders, a gripper comprising clamping jaws adapted to grip the sheet, and mechanisms controlled by said plate cylinder for moving said stop member into and out of position, for opening and closing said jaws, 115 and for moving said gripper from said cylinders to said delivering means and back again. 120

3. In a printing press, the combination, with a rotary plate cylinder, and a rotary impression cylinder, of means for feeding a sheet to said cylinders, means for delivering the sheet after printing, a gripper comprising a pair of jaws adapted to engage said sheet, normally locked power operated means 130

tending to close said jaws, means controlled by said plate cylinder for releasing said power operated means, and mechanism positively controlled by said plate cylinder for moving 5 said gripper from said cylinders to the delivering means and back again.

4. In a printing press, the combination, with a rotary plate cylinder, and a rotary impression cylinder, of means for feeding a 10 sheet to said cylinders, means for delivering the sheet after printing, a gripper comprising jaws adapted to grip said sheet, a rock shaft adapted to be rocked by said plate cylinder, an arm fixed to said rock shaft and 15 carrying said gripper and adapted when rocking said shaft to move the same from said cylinders to said delivering means and back again, a normally locked tubular member rockingly mounted on said rock shaft and 20 connected with said jaws for opening and closing the same, power operated means tending to rock said tubular member into position for closing said jaws, and means controlled by said plate cylinder for releasing said tubu- 25 lar member.

5. In a printing press, the combination, with a rotary plate cylinder, and a rotary impression cylinder, of means for feeding a sheet to said cylinders, means for delivering a 30 sheet after printing, a gripper comprising jaws adapted to grip said sheet, a rock shaft adapted to be rocked by said plate cylinder, an arm fixed to said rock shaft and carrying said gripper and adapted when 35 rocking said shaft to move the same from said cylinders to said delivering means and back again, a tubular member rockingly mounted on said rock shaft and connected with said jaws for opening and closing the same, power 40 operated means tending to rock said tubular member into position for closing said jaws, a locking member carried by said rock shaft and adapted to lock said tubular member relatively thereto, and means controlled by 45 said plate cylinder for setting said locking member into releasing position.

6. In a printing press, the combination, with a rotary plate cylinder, and a rotary impression cylinder, of means for feeding a 50 sheet to said cylinders, means for delivering the sheet after printing, a gripper comprising jaws adapted to grip said sheet, a rock shaft adapted to be rocked by said plate cylinder, an arm fixed to said rock shaft and 55 carrying said gripper and adapted when rocking said shaft to move the same from said cylinders to said delivering means and back again, a tubular member rockingly mounted

on said rock shaft, a notched disk fixed to 60 said tubular member, a rockable locking member carried by said rock shaft and adapted for locking engagement with the notch of said disk, power operated means tending to rock said tubular member on said rock shaft, and mechanism controlled by said plate cylinder 65 for throwing said rockable locking member into releasing position.

7. In a printing press, the combination, with a rotary plate cylinder, and a rotary impression cylinder, of means for feeding a sheet 70 to said cylinders, means for delivering the sheet after printing, a gripper comprising jaws adapted to grip said sheet, a rock shaft adapted to be rocked by said plate cylinder, an arm fixed to said rock shaft and carrying 75 said gripper and adapted when rocking said shaft to move the same from said cylinders to said delivering means and back again, a tubular member rockingly mounted on said rock shaft, a notched disk fixed to said tubular member carried by said rock shaft and adapted for locking engagement with the notch of said disk, power operated means tending to rock said tubular member on said 80 rock shaft, an arm carried by said tubular member, a relatively fixed stop adapted for engagement with said arm and for arresting the rocking movement thereof, and mechanism controlled by said plate cylinder for throwing said rockable locking member into 85 releasing position.

8. In a sheet gripping device for printing presses, the combination with a rotary plate cylinder and a rotary impression cylinder, of means located to the rear of the printing zone 95 with respect to the direction of movement of the sheet for seizing the forward end of a sheet as it is fed between the cylinders, and mechanism for moving said means away from said cylinders during printing engagement 100 between the cylinders and sheet.

9. In a sheet gripping device for printing presses, the combination with a rotary plate cylinder and a rotary impression cylinder, of means located to the rear of the printing zone 105 with respect to the direction of movement of the sheet for seizing the forward end of a sheet as it is fed between the cylinders, mechanism for moving said means away from said cylinders at the linear speed of the latter during printing engagement between the cylinders and sheet and for returning said means 110 to position for seizing the following sheet.

In testimony whereof I hereunto affix my signature.

RUDOLF WEIDE.
